UNITED STATES PATENT OFFICE.

AUGUST SCHROEDER, OF STETTIN, GERMANY.

VOLTAIC PILE.

SPECIFICATION forming part of Letters Patent No. 296,464, dated April 8, 1884.

Application filed September 29, 1883. (No model.)

To all whom it may concern:

Be it known that I, AUGUST SCHROEDER, a subject of the Emperor of Germany, residing at Stettin, in the Empire of Germany, have invented certain new and useful Improvements in Voltaic Piles; and I do hereby declare the following to be a full, clear, and exact description of the same, reference being had to the accompanying drawings, forming part of this specification, wherein—

Figure 1 is a side view of the pile; Fig. 2, a vertical section, and Fig. 3 a bottom view of the same.

The object of my invention is to construct a voltaic pile in such manner that a very distributed electric current may be imparted to any object simply by putting the pile upon this object. The positive and the negative electrodes of the pile are formed in the usual way by plates a $a' \dots b$ $b' \dots$ of those metals or other substances which are generally employed for this purpose. These plates are soldered together two by two, as also well known. They may have any desired shape, but are all entirely flat, with the exception of the top plate, a , and the bottom plate, b , of the pile. The latter is provided with downwardly-extending pins or projections b' , which may be covered, when the pile is to be used, with plates of flannel, so that only the extremities of the projec-

tions b' are visible. Other wet flannel plates, c , are inserted, in the usual manner, between the pairs of the electrodes a b . The top plate, a , has a downwardly-projecting part, a'' , surrounding in some distance all the other plates, 35 and provided at the lower edge with notches, so as to form the triangular teeth a' , which come exactly in the level of the projections b' . For insulating the edges of the plates a b from the downwardly-projecting part of the top 40 plate, a , the india-rubber tube d is interposed.

The pile is put upon the object to which electricity is to be communicated, and a very distributed current will immediately be active between the projections b' and the teeth a' , and 45 pass to the object to which the pile is applied.

What I claim is—

In a voltaic pile, the combination of the bottom plate, b , provided with downwardly-extending projections b' , with the top plate, a , the 50 downwardly-projecting part a'' of which surrounds all the other plates, and comes with its teeth a' in the level of the projections b' , as described, and for the purpose set forth.

In testimony whereof I have hereto set my hand this 4th day of September, A. D. 1883.

AUGUST SCHROEDER.
